UNITED STATES PATENT OFFICE.

WILLIAM F. MÜLLER, OF NEW YORK, N. Y.

DESIGN FOR MATCH-RECEIVER.

Specification forming part of Design No. **6,198**, dated October 8, 1872.

To all whom it may concern:

Be it known that I, WM. F. MÜLLER, of the city, county, and State of New York, have invented and produced a new and original Design for a Match-Receiver, of which the following is a specification:

The design represents an ordinary willow market-basket with a loose cover. The cover on the inside is grated, giving a surface on which to strike the match. The nature of my

design is fully represented in the accompanying drawing, to which reference is made.

I claim as my invention—

The design for a match-receiver, as shown and described.

WM. F. MÜLLER.
